US00D549043S

(12) **United States Design Patent** (10) **Patent No.:** **US D549,043 S**
Beesley et al. (45) **Date of Patent:** **** Aug. 21, 2007**

(54) **SLUSHIE MAKER**(75) Inventors: **Brian K. Beesley**, Draper, UT (US);
Kelly A. Harward, Layton, UT (US)(73) Assignee: **Back to Basics Products, LLC**, Vernon
Hills, IL (US)(**) Term: **14 Years**(21) Appl. No.: **29/245,446**(22) Filed: **Dec. 21, 2005**(51) **LOC (8) Cl.** ..... **31-00**(52) **U.S. Cl.** ..... **D7/378; D7/374**(58) **Field of Classification Search** **D7/372,**
D7/374-378, 306, 384, 386, 412, 282.2;
99/348, 509-511; 241/33, 37.5, 101.01,
241/101.1, 274, 285.2; 366/65, 96, 98, 197,
366/199, 205-206, 241-247, 279, 341

See application file for complete search history.

(74) Attorney, Agent, or Firm—Thorpe North & Western
LLP(57) **CLAIM**The ornamental design for a slushie maker, as shown and
described.**DESCRIPTION**FIG. 1 is an elevated, perspective view of the slushie maker
in accordance with my invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in FIGS. 1-7 are for illustrative
purposes only and form no part of the claimed design.**1 Claim, 6 Drawing Sheets**## U.S. PATENT DOCUMENTS
